US0D1107751S

(12) **United States Design Patent** (10) Patent No.: **US D1,107,751 S**
(45) Date of Patent: ** Dec. 30, 2025

(54) **DISPLAY SCREEN OR PORTION THEREOF
WITH GRAPHICAL USER INTERFACE**

(71) Applicant: **Aristocrat Technologies, Inc.**, Las Vegas, NV (US)

(72) Inventors: **Chad La Guardia**, Austin, TX (US); **Dylan Hindenlang**, Oakland, CA (US)

(73) Assignee: **Aristocrat Technologies, Inc.**, Las Vegas, NV (US)

(**) Term: **15 Years**

(21) Appl. No.: **29/968,362**

(22) Filed: **Oct. 16, 2024**

Related U.S. Application Data

(60) Continuation of application No. 29/946,816, filed on Jun. 11, 2024, now Pat. No. Des. 1,076,967, which is a continuation of application No. 29/907,697, filed on Jan. 8, 2024, now Pat. No. Des. 1,037,307, which is a division of application No. 29/840,736, filed on May 31, 2022, now Pat. No. Des. 1,018,566.

CLAIM

The ornamental design for a display screen or portion thereof with graphical user interface, as shown and described.

DESCRIPTION

The sole FIGURE depicts a front view of a display screen or portion thereof with graphical user interface.

The outermost broken lines in the FIGURE illustrate a display screen or portion thereof and form no part of the claimed design. The remaining broken lines illustrate portions of the graphical user interface that form no part of the claimed design.

1 Claim, 1 Drawing Sheet
